UNITED STATES PATENT OFFICE.

MABEL DEWEY, OF ST. LOUIS, MISSOURI, ASSIGNOR TO LAURA HUBBARD, OF ST. LOUIS, MISSOURI.

WATER-WAVER APPLIANCE.

Application filed December 16, 1925. Serial No. 75,682.

My invention relates to improvements in toilet appliances, and more particularly to an attachment for water-waving combs, whereby the operation of water-waving may 5 be more easily and efficiently accomplished.

My invention has among its other objects, the provision of devices of the kind described, that will be simple, convenient, strong and sturdy in structure, very economical of manufacture, neat and pleasing in appearance, and reliable and satisfactory for use wherever found applicable.

Many other objects and advantages of the construction herein shown and described 15 will be obvious to those skilled in the art to which this invention appertains, from the disclosures herein given.

To this end, my invention consists in the novel construction, arrangement, and combination of parts herein shown and described, and more particularly pointed out 20 in the claims.

In the drawings, wherein like reference characters indicate like or corresponding parts throughout the views,

Figure I is a perspective view of my appliance, shown mounted upon a water-waving comb, the latter being shown in dotted lines; and

Figure II is a longitudinal sectional view 30 through the same.

The operation of water-waving comprises dampening the hair, inserting a pair of combs through the dampened hair, the teeth 35 of the combs being extended in opposite directions so that they may pass one another or intersect. Then the pair of combs are held in this relationship for the desired interval of time, during which time the hair 40 may dry, either entirely or partially, and after which the combs are removed.

The difficult part of the operation or treatment is the fastening of the combs so 45 that they will stay in the desired position for the drying interval. Obviously it would not be practical for the operator to manually hold the combs in their mutually opposed relation until the hair has properly dried. Various makeshifts are used to accomplish 50 this result, some of them being the tying of thread or rubber bands about the combs themselves or about hair pins or the like fastened insecurely thereto, hair pins alone, etc. With these makeshifts, however, it is 55 essential that the operator secure the aid or

assistance of another person before the least degree of success may be obtained. Such a practice is not only oftentimes impossible, but is very undesirable, and where done in commercial establishments or beauty shops 60 is uneconomical. Even when using the methods above described, the combs are apt to become loosened, thus decreasing the effectiveness of the work or at least diminishing 65 its appearance.

In the drawing, wherein I have illustrated one of the preferred embodiments of my invention, C indicates a hair-waving comb of any desired or preferred construction, the same not forming a part of my invention, 70 and comprising generally the teeth 3 extending in series from the handle or back 4. These combs are generally arcuate along their length in order to better fit the head.

The appliance itself is in the form of a 75 clip made of a single piece of material of the desired thickness and resiliency. This clip is preferably made of a strip of material, which is bent or looped at a point intermediate its ends, as at 5, to form a generally U-shaped member having the pair of flat legs 6 and 7, the former being preferably longer than the latter.

These legs, extending in the same direction, converge somewhat toward their free ends, and are reversely bent at the extremities of their free ends, as shown. Thus the legs must be slightly spread when mounting the clip upon the comb, and the tips of the legs will not mar or scratch the comb 80 or the operator as they are rounded off and reversely bent.

The material of the longer leg is slit and pressed outwardly of the plane of the main body portion of said leg to provide the pair 85 of prongs 7 and 8, these prongs being spaced apart lengthwise of the leg and extending in mutually opposite directions, as shown. One of the prongs has its free end toward the free end of the leg 6, and the free end 90 of the other prong toward the looped end 5 of said leg.

In order to strengthen the clip where it has been slit or cut away to form the prongs, I have provided reinforcements in 105 the form of ribs 11, these ribs extending on said leg 6 lengthwise thereof and closely adjacent the prongs 7 and 8.

When using my improved devices upon 110 water-waving combs, these combs are ar-

ranged in pairs, in the usual manner, and one or more clips are mounted upon each of the combs, as shown in the drawing. The combs are arranged in the desired relationship, after which a strand of material as for instance a thread 12 is wound at one end about both the prongs 7 and 8 of one clip in order to anchor said end of the thread, and then the thread is passed over the prongs 7 of the remainder of the clips, anchoring the thread at the last or end clip by passing the same about both the prongs 7 and 8 provided thereon. It will be understood the thread is passed from the clips on one comb to the clips on the other comb, alternately, somewhat in the manner of lacing a shoe lace, or in a zig-zag direction. The pair of combs will be retained for any predetermined periods of time in their desired relationship, as the thread will be anchored at both ends and will draw the combs together at various points along the length of the combs, there being any desired number of clips used, as previously explained. The use of my clips makes the entire operation of hair-waving so simple that no one, other than the operator is required to make a workmanlike job, thus making it possible for one to do this class of work themselves, if they so desire.

Having thus described my invention, it is obvious that various immaterial modifications may be made in the same without departing from the spirit of my invention; hence I do not wish to be understood as limiting myself to the exact construction, form, arrangement and combination of parts herein shown and described, or uses mentioned, except as limited by the claims.

What I claim as new and desire to secure by Letters Patent is:—

1. The combination with a comb, of a clip frictionally mounted thereon and provided with a prong adapted to have one

end of a piece of thread anchored thereon, whereby said thread may draw a similarly mounted comb toward said first comb.

2. A hair-waving appliance adapted to be used in combination with a comb, comprising a pair of spaced legs joined together at one end to form a substantially U-shaped member constructed to straddle said comb, and a prong on one of said legs, extending outwardly toward said joined ends.

3. A toilet appliance comprising a strip of material bent to form a pair of flat legs slightly convergent toward their free ends and adapted to straddle a comb, one of said legs being longer than the other, a pair of prongs struck up from the material of said longer leg, said prongs being spaced apart lengthwise of said leg and extended outwardly of the material thereof, and reinforcement ribs struck up on said leg longitudinally thereof adjacent to and longitudinally of said prongs.

4. A clip adapted to be removably and frictionally mounted upon a hair comb, comprising a pair of spaced flat legs extending in the same direction and joined together at one end whereby they may straddle the comb, and a prong on one of said legs, said prong extending outwardly thereof and toward the joined end, whereby a thread may be wound about said prong in order to draw the comb toward a similarly mounted comb and holding it so for any desired length of time.

5. In a device of the kind described and in combination with a hair comb having teeth extending from the top thereof, of a prong mounted adjacent said top intermediate the ends of said comb and extending in a different direction than said teeth, whereby said prong may form an anchor for a strand of thread.

MABEL DEWEY.
